United States Patent Office

Des. 186,830
Patented Dec. 8, 1959

186,830

MOTION PICTURE CAMERA

Theodore S. Briskin, Chicago, Ill., John E. Davis, Sherman Oaks, Calif., and Robert L. Moore, La Grange Highlands, Ill., assignors to Revere Camera Company, Chicago, Ill., a corporation of Delaware

Application March 27, 1958, Serial No. 50,207

Term of patent 14 years

(Cl. D61—1)

Fig. 1 is a front perspective view of a motion picture camera embodying our new design; and

Fig. 2 is a rear perspective view thereof.

The bottom of the camera is conventional.

The dominant features of our new design are shown in solid lines in the drawing.

We claim:

The ornamental design for a motion picture camera, as shown and described.
